UNITED STATES PATENT OFFICE.

FRED ALESSI, OF WOODRIDGE, NEW JERSEY.

PROPELLER MEANS FOR VESSELS.

Application filed February 15, 1927. Serial No. 168,287.

This invention relates to a new and useful improvement in ship propulsion means and more particularly to a novel and improved propeller shaft and propeller blade assembly 5 wherein the maximum power may be obtained and greater speed results.

One of the objects of my invention is to provide in a propeller shaft a series of radially disposed blades located in advance of 10 each other and positioned at any point between the bow and stern of a vessel so as to constitute an auxiliary power means for creating greater speed.

Another object of my invention is to provide 15 means associated with the main propeller shafts located in suitable water tunnels in the keel of a vessel said shafts being operated through the usual engines which drive the rear propeller blades.

20 In order to more fully understand and appreciate the purpose and objects of my invention reference is had to the accompanying drawing showing a preferred embodiment therein.

25 Fig. 1 is a view showing the series of propeller blades located in the water tunnels adjacent the keel of a vessel.

Fig. 2 is a vertical section showing the blades located in the water tunnels.

30 Fig. 3 is a view showing the blades attached to the shaft.

Fig. 4 is an enlarged and preferred form 35 showing the blades attached to a rod to be fastened or connected to the propeller shaft, and

Fig. 5 is a sectional view from the blades and the said rod.

Referring now to the drawings wherein like reference characters designate corresponding parts throughout the several views, 40 5 designates the body and 6 the keel of any vessel. The keel is provided with water tunnels 7, 8, located on each side of the body and which may be at any suitable point between the bow and the stern. The height of 45 the water tunnel may vary depending upon the draft of the vessel and is preferably curved shaped at its top 9 so as not to offer resistance to the water.

50 The main shaft 10 of the vessel has detachably connected thereto as shown in Fig. 3 for instance, an auxiliary propeller shaft or a rod 11 to which is directly connected a series of radially disposed blades 12 and 55 the main shafts constituting an extension of the auxiliary shaft. As shown by Figs. 1

and 4 of the drawings for instance, two sets of blades are so shown, one directly in advance of the other.

In Fig. 4 I have shown the blades 12 directly connected to the rod 13 in a slightly different manner, said auxiliary shaft or rod being provided with grooves or recesses into which the blades 12 are permanently secured so that the rods may be attached with the 60 blades through the main propeller shaft. It has always been recognized that the greatest power derived from the propeller blades is at the point furthest removed from the shaft and conversely the least amount of power 65 occurs about the propeller shaft itself. In other words the suction created about the propeller shaft, tends to retard the speed of the vessel. Consequently I have arranged a 70 series of propeller blades, one in advance of another, so that the lost motion or power of the first series of blades is compensated for by the adjacent series of blades 12^a. In each 75 instance it will be noted that the radially disposed blades 12 and 12^a, are somewhat curved and extend for a considerable distance along the rods and the main propeller shaft of the vessel. This is somewhat of a departure from the practice of providing propeller blades of considerable length connected to the propeller shaft at right angles thereto. In other words the greatest length 80 of the propeller blades 12, 12^a is longitudinally of the rod and the propeller shaft rather than at right angles thereto. In this 85 way I am enabled to obtain greater surface contact between the blades and the water and consequently increase the efficiency and obtain the maximum power from the propeller shaft and driving engines. 95

To a certain extent my drawings are illustrative of my invention, no attempt being made to set forth the detail of a vessel construction or the water tunnels. The propeller blades mounted in series constitute an auxiliary propulsion means without effecting the main propeller usually at the stern. In other words by providing a series of blades along the propeller shaft and located in water tunnels below the water line of the vessel, 100 I am enabled to obtain greater surface contact between the blades and the water than can be otherwise had. I also realize that the blades may be attached to the power shaft in other manner than herein shown and I 105 therefore do not wish to be limited or restricted to the exact construction illustrated. 110

My invention is directed to the broad idea of mounting a series or plurality of sets of radially disposed blades of considerable length extending along the propeller shaft as distinguished from that type of propeller blades mounted on a shaft at right angles thereto.

Having shown and described my invention what I claim as new is:—

- 10 1. In combination with a ship body having tunnels below the normal water line, main longitudinal power shafts, auxiliary propeller shafts detachably connected to one end of said main shafts constituting prolongations thereof and located in each of said tunnels, two sets of radially disposed blades directly connected to said auxiliary propeller shafts, said blades being disposed in advance of one

another and the length of said blades being considerably greater than the height of the 20 tunnels.

2. In combination with a ship body having tunnels below the normal water line intermediate the ends of said body, longitudinal main power shafts, auxiliary propeller shafts 25 detachably connected to the forward end of each said main shafts constituting prolongations thereof and located in each of said tunnels, two sets of radially disposed blades in advance of each other directly connected to the auxiliary shafts, each of said blades being curved from end to end and of a length considerably greater than the height of the tunnel.

In testimony whereof I affix my signature.

FRED ALESSI.
